W. E. SWALM & A. E. SEXTON.
 APPARATUS FOR TREATING PHOTOGRAPHIC PRINTS AND THE LIKE.
 APPLICATION FILED OCT. 12, 1915.

1,268,406.

Patented June 4, 1918.

UNITED STATES PATENT OFFICE.

WILLIAM E. SWALM AND ARTHUR E. SEXTON, OF LOS ANGELES, CALIFORNIA.

APPARATUS FOR TREATING PHOTOGRAPHIC PRINTS AND THE LIKE.

1,268,406.

Specification of Letters Patent. Patented June 4, 1918.

Application filed October 12, 1915. Serial No. 55,388.

To all whom it may concern:

Be it known that we, WILLIAM E. SWALM and ARTHUR E. SEXTON, both citizens of the United States, residing at Los Angeles, in the county of Los Angeles and State of California, have invented new and useful Improvements in Apparatus for Treating Photographic Prints and the like, of which the following is a specification.

10 This invention relates to apparatus for treating photographic prints and the like, and more particularly to apparatus by means of which a plurality of such prints may be, at the same time, subjected to the modifying 15 action of a fluid which is passed over the surfaces of the prints; the handling of large numbers of photographic prints during the steps required for their completion, as ordinarily carried on, is very tedious, as great 20 care is necessary to expose all surfaces to the modifying influence or action of the fluids with which such prints are successively treated, as, for instance, in the final washing of the prints, every trace of the sodium 25 hyposulfite used in the previous fixing step must be washed out of the prints, and the handling of the prints to insure sufficient exposure to the action of the washing water consumes much time.

30 In accordance with the present invention, means are provided whereby a plurality of prints are held by one edge of each and with each of such edges spaced slightly apart and in such position that a fluid supplied by 35 suitable fluid-supply means may enter the spaces between the edges of adjacent prints so held and be passed over surfaces of the same to modify the prints, or a surface or the surfaces thereof. Provision is made to 40 confine the modifying fluid to paths of travel in films or sheets over such surfaces and in certain cases provision is made for retention of enough of the fluid in a suitable receptacle, in which the prints are treated, 45 to completely submerge the prints during the modifying action.

The invention has for its object to provide apparatus of the general character stated which will be superior in point of 50 relative simplicity and inexpensiveness of construction, combined with positiveness and efficiency of operation, compactness in form, freedom from liability to get out of order, and which will be generally superior 55 in efficiency and serviceability.

With the above and other objects in view, the invention consists in the novel and useful provision, construction, formation, combination and relative arrangement of parts, members, and features, all as hereinafter described, shown in the drawing and finally pointed out in claims. 60

In the drawing:

Figure 1 is a central vertical sectional view of apparatus constructed and organized 65 in accordance with the invention;

Fig. 2 is a central vertical sectional view taken on the line x^2-x^2 , Fig. 1, and looking in the direction of the appended arrows, the view being on an enlarged scale; 70

Fig. 3 is a horizontal sectional view taken on the line x^3-x^3 , Fig. 2, and looking in the direction of the appended arrows;

Fig. 4 is an enlarged fragmentary sectional view taken on the line x^4-x^4 , Fig. 1, 75 and looking in the direction of the appended arrows; and

Fig. 5 is an isometric detail view of certain features of the invention.

Corresponding parts in all the figures are 80 designated by the same reference characters.

Referring with particularity to the drawing, in the embodiment of the invention therein shown, A designates holding means for a plurality of prints a, B designates fluid supply means, C designates a receptacle for a circulating fluid, D designates retarding means for the fluid, and E designates a fluid-discharge duct. 85

The holding means A preferably comprises a U-shaped frame 6 suspended from a handle member 7 by means of links 8 provided one at each end of said handle member 7, a plurality of clamping members 9, each suspended from said handle member 7 90 by links 10, one of which is provided at each end of the clamping members 9, and a closure member 11 adapted to bridge the U-shaped member 6 and be latched thereto by means of spring catches 12, one of which is provided at each terminus of the U-shaped member. The clamping members 9 are secured to the handle member through their respective links 10 and by means of pivots 13 passing through the ends of the links 10, the ends of the links 8 and into the handle member 7. The links 8 and 10 may be twisted to conserve space, and may overlie each other, thus permitting the use of bars of rectangular cross-section in forming the 110

links and avoiding a cumbersome structure. When the closure 11 is in place all of the clamping members are in position in the U-shaped frame 6 and the sheets of paper or photographic prints may be each separated from the next adjacent sheet or print by a clamping member, provision being made in the construction of the clamping members, for the entrance of fluid between the sheets 5 or prints, a simple construction being the formation of outstanding diagonal ridges 9^a and 9^b which project alternately to each side of the respective clamping members 9, the diagonal outstanding projections 9^a of one 10 clamping member co-acting with the outstanding projections 9^b upon the next adjacent clamping member and gripping the paper or sheets to securely hold the same in position, leaving a space for the fluid to 15 pass through the holding means on each side of the sheets so held.

The fluid supply means B preferably comprises a fluid supply pipe or conduit 14 which may be valve-controlled, as at 15, 20 and enter the receptacle C in such manner that the fluid supplied will pass through the spaces between the holder members 9 and the sheets or prints held thereby. A 25 guide plate 16 provided in the receptacle C assists in the distribution of the fluid over the surface of the holder.

The fluid receptacle C preferably comprises a tank having side walls 17 and 17^a, end walls 18 and 18^a, a bottom wall 19, and 30 an apertured partition 20 dividing the receptacle into an upper compartment c and a lower compartment d, the partition 20 serving also as a support for the holding means A. The prints a project, and, in the 35 embodiment of the invention illustrated, depend, from the holding means through the aperture 20^a in the partition 20. The guide member 16, beneath which the supply conduit 14 terminates, is arranged to lie 40 against the wall 18 of the tank at its upper end where it is caught under a rabbeted strip 16^a secured to the wall 18 and from which strip it inclines downwardly and inwardly toward the aperture 20^a in 45 the partition 20. A similar guide member 16^b is arranged with its upper end lying against the wall 18^a of the tank from where it inclines downwardly toward the opening 20^a in the partition, being provided at its 50 lower end with a projection 16^c of such length that the projection will engage wall 18^a when the guide member is in place. A heavy wire spacing frame 21, to which the lower ends of the members 16 and 16^b are 55 secured, holds such members in the proper position and permits removal of the same due to flexibility of the wire, when the member 16^b is drawn upwardly to remove the same from the receptacle. The wedging 60 action of the member 16^b, through the wire 65

frame member 21 upon the member 16 when replacing the same, is apparent. A washer or packing member 22, provided with an orifice 22^a, is interposed between the members 16, 16^b, wire frame 21, and holding 70 means A, on the one hand, and the partition 20 on the other.

The retarding means D comprises, in the embodiment of the invention illustrated, a removable plug or valve e, and an upwardly ranging conduit 23 connected with the fluid receptacle C through an aperture 19^a provided in the bottom wall 19, and extending upwardly to the level at which it is desired to maintain the liquid in the apparatus, an overflow orifice 23^a being provided at such level so that liquid may be discharged through the discharge pipe E with which the conduit 23 communicates through the orifice 23^a. An orifice 24^a is 85 provided in the wall 24 of the conduit 23 at the lowermost point in such conduit, and a plug e is arranged to close the orifice 24^a, a stem 25 being provided by means of which the plug e may be removed from the orifice 90 to permit drainage of the receptacle C. A knob 25 having a downwardly ranging projection 25^b is provided on the end of the stem 25 and a notch 26 adapted to receive the stem 25 is provided at the upper end 95 of the conduit, so that the plug may be held out of the orifice 24^a by the seating of the projection 25^b on the top of the conduit walls when the plug is raised high enough to pass the stem 25 into the notch 26. 100

The discharge pipe E preferably parallels the conduit 23 for a portion of its length and terminates in a chamber 27 below the plug or valve e at the lowermost portion of the conduit wall, so that when the plug e 105 is in raised position it will not be necessary for the fluid to escape from the conduit through the orifice 23^a to the discharge pipe E, but it may pass directly into the discharge pipe E through the orifice 24^a in 110 the conduit wall and out of the apparatus through a suitable drain pipe 28 with which the discharge pipe is suitably connected at its lowermost portion. In the drawing the discharge E and the conduit D are shown 115 as provided for in the construction of the tank at the wall 18^a, though it will be understood that separate pipes suitably connected may be employed. Slightly above the wall 19 of the tank a shield 29 is provided to prevent the fluid from rushing directly out through the orifice 19^a, and this shield is preferably formed of a strip ranging between the end walls of the tank and bent to slope downwardly toward the 120 side walls of the tank, so that the fluid in passing out of the receptacle or tank must travel toward the side walls and under the edges of the shield to the orifice 19^a. A duct 30 passes through the partition 20 and con- 130

nects the lower compartment *d* of the tank with the normal atmosphere at a point above the liquid level in the apparatus.

The operation, method of use and advantages of the improved apparatus will be readily understood from the foregoing description, taken in connection with the accompanying drawing and the following statement:

- 10 If, for instance, it is desired to wash a number of photographic prints, they are placed in holding means or holders such as A by first releasing closure 11 from the latches 12, whereupon all of the members 9 may be moved out of the U-shaped frame and a print placed with one edge against such frame and the first of the series of members 9 placed over the print and another print placed over the holder, it being in turn 15 clamped by the next holder of the series, and so on until the holder is filled, one print being held between each member 9 and the next adjacent member 9 or the frame 6 or the closure 11. When all of the members are in 20 the U-shaped frame the closure is snapped into place, binding the mass of prints in the holder. All this may be conveniently performed in the dark room and with the holder and prints submerged in whatever photographic bath they may be in during the 25 clamping stage, with the prints lying flat one upon the other save where they are separated at the edges by the holders. After a holder has been filled as described the prints 30 will stick together and may easily be removed from the bath and introduced through the aperture 20^a in the partition 20 of the receptacle C where they will be suspended by the holder which rests with its 35 edges on the partition. The receptacle is empty when the prints are introduced therein, and after positioning of the prints, the plug *e* closing the orifice 24^a, the fluid with 40 which the prints are to be washed or otherwise treated is admitted by opening the valve of the fluid supply means B. The fluid rising in the upper compartment *c* finds its way through the spaces between the 45 holders and the prints and flows over the surfaces of the prints into the lower compartment *d*. As the liquid level in the lower compartment rises it permits separation of the portions of the sheets which are massed together and in superficial contact with each 50 other and causes divergence of the sheets or prints. The liquid level rises until it reaches the orifice 23^a in the wall of the conduit 23, which orifice is preferably high enough to insure receptacle C filling with 55 liquid to a point above the handle member 7, which may thus also be subjected to the cleansing action of the liquid. The rate of liquid flow over the surfaces of the sheets or prints may be regulated by the valve 15 of 60 the fluid-supply means B, and the prints a

remain separated, diverging toward their free ends as long as the flow or circulation of liquid is maintained. After the prints have been thoroughly washed or sufficiently treated, the fluid may be shut off by means 70 of the valve 15 and the plug *e* raised to permit the drainage of the receptacle, after which the prints may be removed by means of the holder, and a new batch inserted.

It is manifest that many variations may 75 be made, departing from the specific disclosures herein, both as to construction of apparatus and employment of fluids of various natures, without departing from the spirit of this invention and the terms of the 80 following claims.

Having thus disclosed our invention, we claim and desire to secure by Letters Patent:

1. In apparatus of the character disclosed, means for holding a plurality of prints or 85 the like by only one edge of each and with each edge held in spaced relation to one edge of the next adjacent print, said means being constructed to allow fluid to flow therethrough and over the surfaces of the prints, 90 and means for so supplying a flowing fluid.

2. In apparatus of the character disclosed, means for positioning in the path of a circulating fluid a plurality of prints or the like held by only one edge of each and with 95 the edges disposed in spaced relation to one another, and means for supplying a flowing fluid to a point above the holding means, said means being constructed to allow fluid to pass therethrough and over the prints 100 held thereby.

3. In apparatus of the character disclosed, means for positioning in the path of a circulating fluid a plurality of prints or the like each held by only one edge and with 105 such held edges each in spaced relation to one edge of the next adjacent print, and means for supplying a moving fluid; said positioning means comprising a plurality of spacer members adapted to alternate with 110 the prints, means for directing the circulating fluid to a point over the print holding means whereby said fluid will pass through said means and over said prints, and means for securing said members in clamping position on said prints and whereby said prints are permitted to diverge toward their free ends under the influence of said moving fluid.

4. In apparatus of the character disclosed, 120 a print-receiving tank having an upper chamber and a lower chamber, a print-holding device in the upper chamber for holding a plurality of prints in the lower chamber by one of their edges only and each with 125 the edge so held in spaced relation to the edge of the next adjacent print, and means for supplying a fluid to said upper chamber.

5. In apparatus of the character disclosed, 130 a print-receiving tank having an upper

chamber and a lower chamber, a print-holding device whereby a plurality of prints may be held in the lower chamber by one of their edges only and each with the edge so held in spaced relation to the edge of the next adjacent print, said chamber communicating with one another and means for supplying a fluid to said upper chamber, whereby said fluid will pass into the lower chamber and over the prints.

6. In apparatus of the character disclosed, a print-receiving tank having an upper chamber and a lower chamber, a print-holding device whereby a plurality of prints may be held by one of their edges only and each with the edge so held in spaced relation to the edge of the next adjacent print, and means for supplying a fluid to said upper chamber; said print-holding device being positioned in said upper chamber and permitting the projection of said prints into said lower chamber; said holding device comprising a plurality of spacer members adapted for insertion between the holding edges of the prints and permitting the flow of fluid between such edges.

7. In apparatus of the character disclosed, a print-receiving tank having an upper chamber and a lower chamber, a print-holding device whereby a plurality of prints may be held by one of their edges only and each with the edge so held in spaced relation to the edge of the next adjacent print, and means for supplying a fluid to said upper chamber; said print-holding device being positioned in said upper chamber and permitting the projection of said prints into said lower chamber; said holding device com-

prising a plurality of spaced members adapted for insertion between the held edges of the prints and permitting the flow of fluid between such edges; said tank and chamber being constructed to provide for a circulation of said fluid.

8. In apparatus of the character disclosed, a tank, a holder adapted to be positioned in said tank and comprising spaced members adapted for engagement with one edge only of prints or the like and adapted to permit the flow of fluid between said spaced members whereby a circulating fluid may wash the surfaces of the prints so held and during such washing action cause the divergence of the free ends thereof, and means for supplying a fluid between the spacer members.

9. In apparatus of the character disclosed, a tank, a holder adapted to be positioned in said tank and comprising spaced members adapted for engagement with one edge only of prints or the like and adapted to permit the flow of fluid between said spaced members whereby a circulating fluid may wash the surfaces of the prints so held and during such washing action cause the divergence of the free ends thereof, and means for supplying a fluid between the spacer members; said holder being held against movement with said circulating fluid.

In testimony whereof, we have signed our names to this specification in the presence of two subscribing witnesses.

WILLIAM E. SWALM,
ARTHUR E. SEXTON.
